DESIGN FOR A CRIBBAGE BOARD

Charles R. Reeves, Detroit, Mich.

Application May 21, 1945, Serial No. 119,661

Term of patent 14 years

(Cl. D34—5)

To all whom it may concern:

Be it known that I, Charles R. Reeves, a citizen of the United States of America, residing at Detroit, in the county of Wayne and State of Michigan, have invented a certain new, original, and ornamental Design for a Cribbage Board, of which the following is a specification, reference being had to the accompanying drawing, forming a part thereof.

The single figure is a perspective view of a cribbage board showing my new design.

I claim:

The ornamental design for a cribbage board, substantially as shown.

CHARLES R. REEVES.
